Primary Examiner — Darlington Ly(74) *Attorney, Agent, or Firm* — McAndrews Held & Malloy, Ltd.(57) **CLAIM**

The ornamental design for a power tool, as shown and described.

DESCRIPTION

FIG. 1 is a front-bottom perspective view of a power tool showing my new design;

FIG. 2 is an enlarged front-bottom perspective view thereof;
FIG. 3 is an enlarged front elevation view thereof;
FIG. 4 is an enlarged rear elevation view thereof;
FIG. 5 is an enlarged right side elevation view thereof; the left side elevation view being a mirror image thereof;
FIG. 6 is an enlarged top plan view thereof;

FIG. 7 is an enlarged bottom plan view thereof; and,
FIG. 8 is a rear-bottom perspective view thereof.
The dashed broken lines in the figures represent environment and portions of the power tool that form no part of the claimed design.

The dot-dash broken lines in the figures represent a boundary line that forms no part of the claimed design.

1 Claim, 8 Drawing Sheets(56)
